[57] CLAIM

The ornamental design for a combined safety switch and alarm unit, as shown and described.

DESCRIPTION

FIG. 1 is an exploded perspective view of a combined safety switch and alarm unit showing my new design, with the alarm unit broken away in the center portion to indicate indeterminate length;

FIG. 2 is a front elevational view of the safety switch portion;

FIG. 3 is a rear view thereof;

FIG. 4 is a right side elevational view thereof, with the cord broken away to indicate indeterminate length;

FIG. 5 is a left view thereof;

FIG. 6 is a top view thereof;

FIG. 7 is a bottom view thereof;

FIG. 8 is a right side elevational view of the alarm unit portion;

FIG. 9 is a left view thereof;

FIG. 10 is a front view thereof;

FIG. 11 is a rear view thereof;

FIG. 12 is a top view thereof; and,

FIG. 13 is a bottom view thereof.
